CIRCUIT INTERRUPTER

George B. Cushing, Turtle Creek, Pa., assignor to
Westinghouse Electric Corporation, East Pitts-
burgh, Pa., a corporation of Pennsylvania

Application May 15, 1951, Serial No. 226,507

25 Claims. (Cl. 200—150)

1

This invention relates to circuit interrupters in general, and, more particularly, to arc-extinguishing structures therefor.

A general object of my invention is to provide an improved fluid blast type of circuit interrupter which will be more easily inspected, and which will be more economical to manufacture and to service.

A further object is to provide an improved circuit interrupter which will have reduced dimensions, and yet despite such reduced size, will have as equally effective operating characteristics as interrupters of the same type heretofore manufactured.

Still a further object is to provide an improved arc-extinguishing structure, the walls of which are of cylindrical form in which one or more venting inserts are provided. Preferably such inserts are mounted in apertures provided in the walls of the casing so that the insert may extend internally across the casing.

Further objects and advantages will readily become apparent upon reading the following specification taken in conjunction with the drawings in which:

Figure 1 is a side elevational view, partially in vertical section, of an improved arc-extinguishing unit embodying my invention, the contact structure being shown in the partially open circuit position;

Fig. 2 is an end elevational view of the insert employed in the extinguishing unit of Fig. 1;

Fig. 3 is a side elevational view of the insert pictured in Fig. 2;

Fig. 4 is a plan view in section, taken along the line IV—IV of Fig. 3;

Fig. 5 is a side elevational view of a complete circuit interrupter, the tank being partly broken away to show the internal construction thereof, and the contact structure being shown in the closed circuit position; and

Fig. 6 is a plan view in section taken along the line VI—VI of Fig. 1.

Referring to the drawings, and more particularly to Fig. 1 thereof, the reference numeral 1 designates a terminal bushing extending downwardly from the cover 2 of a tank 3, with particular attention being directed to Fig. 5, the latter showing a complete circuit interrupter of the type considered.

Extending interiorly through the terminal bushing 1 is a terminal stud 4 which is exteriorly threaded. The lower end of the terminal stud 4 is threadedly secured to, and clamped by, a contact foot 5, bolts 6 being employed to clamp

2

the contact foot 5 to the lower end of the terminal stud 4.

Preferably, the contact foot 5 is an integral part of a cup-shaped top dome casting 7, the lower end of which is internally threaded, as at 8, to fixedly maintain in position an insulating cylindrical casing 10.

A relatively stationary pressure-generating contact 11 is pivotally mounted interiorly within the top dome casting 7 in any suitable manner, and cooperates with an intermediate contact 12 to establish a pressure-generating arc 13 within a pressure-generating chamber, generally designated by the reference numeral 14.

15 The intermediate contact 12 is spring-biased downwardly, in the opening direction, and is moved upwardly in the closing direction against the spring pressure by a lower movable rod-shaped interrupting contact 16. Preferably, the 20 interrupting contact 16 is fixed to the end of a conducting bridging member 17 (Fig. 5) which is vertically actuated in its opening and closing movements by an insulating operating or lift rod 18. The operating rod 18 may be actuated 25 by any suitable operating mechanism, which forms no part of my invention.

It will be observed that the diametrical opposite walls of the casing 10 have mounting apertures 19 provided therein, within which is placed and mounted a multi-orifice venting insert, generally designated by the reference numeral 20. The multi-orifice venting insert 20 is preferably molded out of any suitable insulating molding material so that it is an integral unit. Figs. 2-4 more clearly show the construction of the unitary multi-orifice venting insert 20. It will be noted that the venting insert 20 has two pairs of venting passages 21, which extend from a central passage 22 to the region exteriorly of the extinguishing unit 23, as more clearly shown in Figs. 1 and 6.

Also the venting insert 20 has a pair of inlet passages 24 which communicate between the central passage 22 and the interior 25 of the extinguishing unit 23. Fig. 6 may be referred to in this connection.

Preferably, the venting insert 20 has a pair of ring-shaped end portions 26 which fit within the mounting apertures 19 of the casing 10. The outer ends of the venting passages 21 extend laterally beyond the ring-shaped end portions 26 to cooperate with a retainer ring 27, more clearly shown in Figs. 1 and 6. Machine screws 28 fixedly secure the retainer ring 27 in position, and their interior ends 28a preferably main-

tain in position a centrally apertured lower closure plate 29, through which the lower movable interrupting contact 16 moves during the opening and closing operations of the interrupter.

The operation of my improved arc-extinguishing unit will now be described. During the opening operation, suitable mechanism, responsive either to manual operation or to the existence of overload conditions existing in the circuit controlled by the interrupter, causes downward opening motion of the insulating lift rod 18 (Fig. 5).

The downward opening motion of the lift rod 18 causes corresponding downward opening motion of the conducting bridging member 17 and the two interrupting contacts 16 disposed at the outer edges of the bridging member 17.

Referring to Fig. 1, the downward opening motion of the rod-shaped interrupting contact 16 will first permit the contact pressure spring, not shown, associated with the pressure-generating contact 11 to permit slight downward travel of the pressure-generating contact 11. Further downward opening travel of the interrupting contact 16 will be followed by the intermediate contact 12 due to the accelerating spring pressure, not shown, associated therewith. The consequent separation between the pressure-generating and intermediate contacts 11, 12 will cause the establishment of a pressure-generating arc 13, as shown in Fig. 1.

Continued downward opening motion of the interrupting contact 16 will result in a separation between the intermediate and interrupting contacts 12, 16, the intermediate contact 12 having been halted in its downward opening travel by a suitably disposed stop, not shown. This results in the establishment of an interrupting arc 30 between the intermediate and interrupting contacts 12, 16 through the centrally disposed arcing passage 22 of the venting insert 20, as shown more clearly in Fig. 1.

Since liquid, such as oil 31, fills the tank 3 to the level 32 (Fig. 5) oil will completely fill the extinguishing unit 23, and the establishment of a pressure-generating arc 13 will generate pressure within the pressure-generating chamber 14 internally within the casing 10. This pressure will be communicated downwardly through the region 25 and will act through the inlet passages 24 in the manner indicated by the arrows of Figs. 1, 3, 4 and 6. Also oil will be forced downwardly through the top orifice 33 of the insert 20, and upwardly through the bottom orifice 34 of the insert 20, as more clearly shown in Fig. 1.

The orifices 33 and 34, together with the intermediate orifices 35, 36, the latter being disposed intermediate the venting passages 21 and the central inlet passage 24, all serve to direct fluid, in this instance oil, through the central arc passage 22 and into engagement with the interrupting arc 30.

Following contact with the interrupting arc 30, such liquid passes out of casing 10 through the two pairs of exhaust passages 21, as indicated by the arrows in Figs. 1, 3, 4 and 6. Deionization and extinction of the interrupting arc 30 soon follows, and the circuit is interrupted. The interrupting contact 16 moves downwardly with the cross-bar 17 and lift rod 18 to the dotted line open circuit position, as indicated by the reference numeral 37 of Fig. 5, thereby introducing two serially related isolating gaps in the circuit.

During the closing operation, it is merely necessary to cause upward movement of the operating rod 18, which raises the cross-bar 17 and the interrupting contacts 16. The latter enter the apertures 38 provided in the extinguishing units 23, pass along the arcing passages 22, pick up the intermediate contacts 12 and raise the latter into contacting engagement with the pressure-generating contacts 11 against the spring pressure associated with the intermediate contacts 12. The circuit is then closed. Obviously, in the closed circuit position of the interrupter the electrical circuit therethrough includes the terminal stud 4, extending through the left-hand terminal bushing 1, the contact foot 5, pressure-generating contact 11, intermediate contact 12, lower interrupting contact 16, conducting bridging member 17 and through the right-hand extinguishing unit 23 in similar fashion to the right-hand terminal bushing 39 (Fig. 5).

Referring to Fig. 5, it will be observed that I show modified arc-extinguishing units 40 serially connected, and each unit 40 employing a pair of venting inserts 20, the latter being angularly displaced from each other, as shown in Fig. 5, to thereby insure a more uniform dissemination of the exhaust arc gases exteriorly of the extinguishing units 40. In other words, in order to prevent a possible external flashover, it is desirable to prevent the exhaust arc gases, which are of a low dielectric strength, from being too concentrated at any one point. Therefore, by angularly displacing the position of the venting inserts 20, as shown in Fig. 5, the arc gases are more uniformly disseminated, and yet advantage may be taken of my improved insert construction for interrupting the higher voltages, where a longer length of interrupting arc 30 may have to be interrupted.

Preferably, where only two venting inserts are employed for each extinguishing unit, the inserts are angularly disposed approximately 90 degrees so that the vertical spacing between axes of the inserts can be less than the diameter of the end portions 26 without interference, and orifices can be spaced at regular intervals in the interrupting gap. Also, in addition to the retainer ring 27 for the lower venting insert 20, an additional retainer ring 41 may be employed on the top side of the upper venting insert 20, as shown in Fig. 5.

Heretofore, the multi-orifice structure associated with the interrupting arc 30 has been formed by the contiguous superpositioning of a plurality of fibre insulating plates, suitably configured. Reference may be had to United States Patent 2,467,760, issued April 19, 1949 to Leon R. Ludwig, Benjamin P. Baker and Winthrop M. Leeds, and assigned to the assignee of the instant application for a description of the general type of plates which were used.

Common practice, such as disclosed in this patent, employed fibre plates $\frac{1}{4}$ or $\frac{1}{8}$ inch thick, in quantity exceeding 30. These, together with special fibre plates, end plates and castings were bolted into a unit with insulated tie rods. Although such a construction has proved to be highly effective in extinguishing the arcs, yet it is obvious that the manufacturing cost is appreciable because large areas of the original fibre must be removed to provide oil channels, openings for tie rods, vent passages and clearance for the contacts. Moreover, a fibre wall must be maintained between the high pressure region within the arc-extinguishing stack and the oil external to the

stack; otherwise leakage will upset the controlled oil flow. However, because of its laminar construction, no longitudinal tensile strength can be derived from this wall, and tie-rods must be provided for this function. It has generally been necessary to have an extremely large number of components which must be carefully manufactured and assembled. Replacement of the orifices can be accomplished only by complete disassembly, and the stack length is variable according to the moisture content of the fibre plates.

The design which I propose, and which is described above, is a multi-orifice structure embodied in a heavy walled, high strength, insulating tube. The venting means 20, which I provide in the region of the interrupting gap 30, is maintained in position by a tubular retainer 27, which is slid on the bottom of the interrupter and attached by screws 28. The cooperation between the upper edge of the retainer ring 27 and the lower side 42 (Fig. 1) of the lower venting passage 21 prevents shifting and rotation of the venting means 20 after installation.

This multi-orifice venting insert 20, placed in a tube in the disclosed manner, possesses several advantages. First, the tube 10 can be designed to contain the internal pressures, and yet can be relatively thin-walled because of its favorable circular shape. So designed, it also will withstand tensile stresses along its axis, eliminating any need for tie-rods, which were used in the construction set out in Patent 2,467,760. Additional space will accordingly be available for internal oil flow.

The venting means 20, which I have illustrated, makes possible the incorporation of multi-flow action in a tubular structure with several advantages. It is extremely simple, being a single molded insert installed in holes drilled on the diameter of tube 10; yet this simplicity incorporates all of the inlet channels and vent passages, commonly supplied in the interrupting gap of a multi-flow type of interrupter, as set out in the aforesaid patent.

There is little opportunity for leakage, the intersection of the tube 10 and venting means 20 being a simple curve which may, if desired, be sealed with an O ring type gasket. The tubular construction of the walls enclosing the venting passages 21 in the venting insert 20 provides considerable resistance to pressures within chamber 25.

Internal forces within chamber 25 tending to expel the venting insert 20 from the arc-extinguishing unit 23 are balanced, giving zero net horizontal force. Replacement of the venting means 20 entails simply removal of retainer ring 27, attached with screws 28 and a complete new set of interrupting orifices 33-36, provided by a new insert 20, will return a heavily used extinguishing unit 23 to "good as new" condition. Functionally, space not required for venting is available as large cross-sectional oil flow channels; and the elimination of the tie-rows, previously used, will permit the entire arc-extinguishing unit to have smaller external dimensions.

Where higher voltage applications require additional multi-flow orifices, the venting means 20 can be installed in multiple, as indicated in Fig. 5, successive units 20 being oriented on other diameters around tube 10. By this means, the vented gas can be distributed around the interrupter to reduce the hazard of external flashover. Also spacing between adjacent venting means 20 can be smaller than the diameter of the ends

of these components. The distribution of vented gas would be particularly desirable in a low oil content type of breaker where the gases are restricted by the closely encasing tubing.

5 The venting means 20 could also be applied to an impulse type of interrupter, where a piston substitutes for the pressure-generating arc 13 in raising the internal pressure of the interrupter and thereby causing oil flow. Thus certain features described in my invention make it particularly well adapted to low oil content breakers of either the self-generated gas blast or impulse type.

The foregoing description of two embodiments 15 of my invention show how I have constructed a multi-flow type of interrupter in a tube with means of venting the tubular constructed interrupter to give multi-flow characteristics. Also my improved interrupter gives improved interrupting performance by providing larger section oil channels with no increase in over-all size. The foregoing construction permits easy replacement 20 of interrupting orifices, and the inserts can readily be formed of a suitable molding material.

25 Although I have shown and described specific structures, it is to be clearly understood that the same were merely for the purpose of illustration, and that changes and modifications may readily be made therein by those skilled in the art, without departing from the spirit and scope of the 30 appended claims.

I claim as my invention:

1. A circuit interrupter including a casing, means establishing an arc within the casing, interrupting passage structure for extinguishing the arc, a venting insert having an exhaust passage constituting at least a portion of said interrupting passage structure and exhausting fluid from the arc away from the interrupting passage 35 structure and out of the casing, the side wall of the casing having an aperture to assist in supporting the insert, and the insert being laterally removable from the side wall of the casing.

2. A circuit interrupter including a casing, a 40 pair of mounting apertures provided diametrically in the side walls of the casing, means for establishing an arc within the casing, interrupting passage structure for extinguishing the arc, a venting insert having exhaust passages therein constituting at least a portion of said interrupting passage structure and exhausting fluid from the arc and out of the casing, the venting 45 insert being mounted in the apertures and extending diametrically across the casing, and the venting insert being laterally removable from the side wall of the casing.

3. A circuit interrupter including a casing, means establishing an arc within the casing, interrupting passage structure for extinguishing the arc, a plurality of venting inserts having exhaust 50 passages and constituting at least a portion of said interrupting passage structure, each venting insert exhausting fluid from the arc out of the casing, a pair of apertures provided in the 55 side wall of the casing angularly displaced to mount the venting inserts, and each venting insert being laterally removable from the side wall of the casing.

60 4. A circuit interrupter of the liquid break type including a tubular casing, means for establishing a pressure-generating arc and a serially related interrupting arc within the casing, the side walls of the casing adjacent the interrupting arc having apertures provided therein, and a venting 65 insert laterally removable from the side wall of the casing.

70 5. A circuit interrupter including a tubular casing, means for establishing a pressure-generating arc and a serially related interrupting arc within the casing, the side walls of the casing adjacent the interrupting arc having apertures provided therein, and a venting 75 insert laterally removable from the side wall of the casing.

of the casing extending between the apertures internally across the casing.

5. A circuit interrupter of the liquid break type including a tubular casing, means for establishing a pressure-generating arc and a serially related interrupting arc within the casing, the side walls of the casing adjacent the interrupting arc having apertures provided therein, a plurality of venting inserts laterally removable from the side wall of the casing extending between the apertures internally across the casing, and each insert being angularly displaced with respect to the adjacently disposed insert to disseminate the exhaust arc gases.

6. A circuit interrupter including a casing, means establishing an arc within the casing, a multi-orifice insert having one or more exhaust passages therein for exhausting fluid away from the arc and out of the casing, the side wall of the casing having an aperture to assist in supporting the multi-orifice insert, and the multi-orifice insert being laterally removable from the side wall of the casing.

7. A circuit interrupter including a pressure chamber, a longitudinal casing defining at least a part of said pressure chamber, means for establishing an arc within the longitudinal casing, a pair of mounting apertures provided diametrically in the side walls of the casing, a multi-orifice insert having one or more exhaust passages therein for exhausting fluid away from the arc and out of the casing, the multi-orifice insert extending interiorly across the casing between said apertures, and the multi-orifice insert being laterally removable from the side wall of the casing.

8. A circuit interrupter including a cylindrical casing, means establishing an arc within the casing generating pressure therein, a plurality of multi-orifice inserts laterally removable from the side wall of the casing, the side walls of the casing having apertures provided therein so that the multi-orifice inserts may extend internally across the casing, and each multi-orifice insert being angularly displaced with respect to the adjacently disposed multi-orifice insert to disseminate the exhaust arc gases.

9. A circuit interrupter of the liquid break type including a tubular casing, means for establishing a pressure-generating arc and a serially related interrupting arc within the casing, the side walls of the casing adjacent the interrupting arc having apertures provided therein, and a multi-orifice insert extending between the apertures internally across the casing and laterally removable from the side wall of the casing.

10. A circuit interrupter of the liquid break type including a tubular casing, means for establishing a pressure-generating arc and a serially related interrupting arc within the casing, the walls of the casing adjacent the interrupting arc having apertures provided therein, a plurality of laterally removable multi-orifice inserts extending between the apertures internally across the casing, and each multi-orifice insert being angularly displaced with respect to the adjacently disposed multi-orifice insert to disseminate the exhaust arc gases.

11. A circuit interrupter including a cylindrical casing, means including a movable contact for establishing an arc within the casing generating pressure therein, a removable venting insert having at least a pair of opposed exhaust passages and one or more inlet passages provided therein, said insert having a centrally-disposed arc passage to accommodate the movable con-

tact, and the walls of the casing having apertures provided therein so that the insert may extend internally across the casing with the opposed exhaust passages exhausting through the apertures.

12. A circuit interrupter including a pressure chamber, a longitudinal casing defining at least part of said pressure chamber, apertures provided diametrically in the walls of the casing, a removable venting insert extending internally of the casing between the apertures, and said venting insert having at least a pair of opposed exhaust passages provided therein to exhaust in substantially opposite directions out of the apertures.

13. A circuit interrupter including a cylindrical casing, means establishing an arc within the casing generating pressure therein, a plurality of removable venting inserts, the walls of the casing having apertures provided therein so that the inserts may extend internally across the casing, each insert having at least a pair of opposed exhaust passages provided therein, the exhaust passages exhausting in substantially opposite directions out through the apertures, and each insert being angularly displaced with respect to the adjacently disposed removable insert to disseminate the exhaust arc gases.

14. A circuit interrupter of the liquid break type including a tubular casing, means for establishing a pressure-generating arc and a serially related interrupting arc within the casing, the walls of the casing adjacent the interrupting arc having apertures provided therein, a removable venting insert having at least a pair of exhaust passages provided therein extending between the apertures internally across the casing, and the exhaust passages exhausting in substantially opposite directions out through the apertures.

15. A circuit interrupter including a cylindrical casing, means including a rod-shaped movable contact for establishing an arc within the casing generating pressure therein, a removable venting insert having a centrally disposed passage provided therein for accommodating movement of the rod-shaped contact, said venting insert also having one or more exhaust passages and at least a pair of inlet passages, the walls of the casing having apertures provided therein so that the venting insert may extend internally across the casing, and the exhaust passages exhausting in substantially opposite directions out through the apertures.

16. A circuit interrupter including a cylindrical casing, means establishing a pressure-generating arc within the casing, means including a rod-shaped movable interrupting contact for establishing an interrupting arc within the casing, fluid under pressure from the pressure-generating arc flowing toward the interrupting arc to effect the latter's extinction, a removable venting insert having a centrally disposed passage for accommodating motion of the movable interrupting contact, said venting insert having at least a pair of opposed exhaust passages and at least a pair of cooperating inlet passages, and the walls of the casing having apertures provided therein so that the venting insert may extend internally across the casing.

17. A circuit interrupter of the liquid break type including an arc-extinguishing unit immersed in liquid, the unit including a cylindrical casing, contact means including a rod-shaped movable interrupting contact for establishing a

pressure-generating arc and a serially related interrupting arc within the casing, a removable venting insert having a centrally disposed passage therein to accommodate motion of the rod-shaped movable interrupting contact, said venting insert also having at least a pair of opposed exhaust passages and at least a pair of cooperating inlet passages, and the walls of the casing having apertures provided therein so that the insert may extend internally across the casing.

18. A circuit interrupter including a casing, means establishing an arc within the casing, a multi-orifice insert having one or more exhaust passages therein for exhausting fluid away from the arc and out of the casing, the side wall of the casing having an aperture engaged by the multi-orifice insert to assist in supporting the multi-orifice insert, the multi-orifice insert being laterally removable as a unit from the side wall of the casing, and a space on each side of the multi-orifice insert between the insert and the inside wall of the casing.

19. A circuit interrupter including a casing, means including a rod-shaped contact movable longitudinally of the casing for establishing an arc within the casing, a multi-orifice insert having one or more exhaust passages therein for exhausting fluid away from the arc and out of the casing, said multi-orifice insert having an arc passage extending longitudinally of the casing and in which the movable rod-shaped contact moves, the side wall of the casing having an aperture to assist in supporting the multi-orifice insert, the multi-orifice insert being laterally removable from the side wall of the casing, a space on each side of the multi-orifice insert between the insert and the inside wall of the casing, and one or more inlet passages leading from the space in the casing to the arc passage.

20. A circuit interrupter including a cylindrical casing, means establishing an arc within the cylindrical casing, a multi-orifice insert having one or more exhaust passages therein extending out of the casing for exhausting fluid away from the arc and out of the casing, the side wall of the cylindrical casing having an aperture to assist in supporting the multi-orifice insert, and the multi-orifice insert including its one or more exhaust passages having transverse dimensions no greater than the dimensions of the aperture and being laterally removable from the side wall of the casing through the aperture.

21. A circuit interrupter including a cylindrical casing of insulating material, means establishing an arc within the cylindrical casing longitudinally thereof, a multi-orifice insert of insulating material having one or more exhaust passages therein for exhausting fluid away from the arc and laterally out of the cylindrical casing, the side wall of the cylindrical casing having an aperture to assist in supporting the multi-orifice insert and through which the fluid exhausts, the multi-orifice insert being laterally removable from the side wall of the cylindrical casing, and a space having the shape of a segment of a circle on each side of the multi-orifice insert between the insert and the inside wall of the cylindrical casing.

22. A circuit interrupter including a casing, means including a movable rod-shaped contact for establishing an arc within the casing, a multi-

orifice insert having one or more exhaust passages therein for exhausting fluid away from the arc and out of the casing, said multi-orifice insert having a central arc passage in which the movable rod-shaped contact moves, the side wall of the casing having an aperture into which one end of the multi-orifice insert extends to assist in supporting the multi-orifice insert, said rod-shaped contact being movable to a position entirely out of the multi-orifice insert, and the multi-orifice insert then being laterally removable from the side wall of the casing through said aperture.

23. A circuit interrupter including a pressure chamber, a longitudinal casing defining at least part of said pressure chamber, apertures provided diametrically in the walls of the casing, a removable venting insert extending internally of the casing between the apertures, said venting insert having at least a pair of opposed exhaust passages provided therein to exhaust in substantially opposite directions out of the apertures, the whole venting insert which extends between the two apertures being laterally removable from the side wall of the casing through one of the apertures, and a retaining means disposed externally of the casing and engaging a portion of the venting insert to assist in retaining the same in a fixed position in the casing.

24. A circuit interrupter including a casing, means establishing an arc within the casing, a multi-orifice insert having one or more exhaust passages therein for exhausting fluid away from the arc and out of the casing, the side wall of the casing having an aperture to assist in supporting the multi-orifice insert, the multi-orifice insert being laterally removable from the side wall of the casing through the aperture, and a retaining member disposed externally of the casing and engaging a portion of the multi-orifice insert to assist in retaining the same in a fixed position in the casing.

25. A circuit interrupter including a casing, means including a movable rod-shaped contact for establishing an arc within the casing, a multi-orifice insert having one or more exhaust passages therein for exhausting fluid away from the arc and out of the casing, said multi-orifice insert having a central arc passage through which the movable rod-shaped contact moves, the side wall of the casing having an aperture to assist in supporting the multi-orifice insert, the multi-orifice insert being laterally removable from the side wall of the casing, and at least one end of the central arc passage being relatively open during the arc drawing process to permit fluid in the casing adjacent the multi-orifice insert to flow into the arc passage.
